(57) **ABSTRACT**

This invention relates to a pocket for portable telephone in clothes. The pocket is provided in cloth such as front body cloth or sleeve cloth in a jacket, and front body cloth or back body cloth in slacks. The pocket comprises a lower section provided horizontally in cloth with the width of 6 cm to 11 cm, and an upper section provided horizontally to the lower section with the same width thereof. A bottom bag made of stretchy cloth with the comparatively shallow depth is sewed to the lower section to be suspended behind the cloth. A head bag with the height of 2 cm to 4 cm is sewed to the upper section to oppose upward to the bottom bag. The number of the upper section is not limited to one, but the upper section with the width of 2 cm to 3 cm can be provided above both sides of the lower section.

FIG. 8B

FIG. 9**FIG. 10****FIG. 11****POCKET FOR PORTABLE TELEPHONE IN CLOTHES**

FILED OF THE INVENTION

The present invention relates to a pocket in clothes such as a jacket or slacks, or more precisely, a pocket for a portable telephone in clothes.

BACKGROUND OF THE INVENTION

As a portable telephone has been miniaturized and lightened, it has recently become more popular and more easily carried. It is primarily carried in a pocket in a jacket or slacks.

When carrying a portable telephone in a pocket of slacks, especially a side pocket thereof, it is difficult to take out only the portable telephone from the pocket, since in many cases there are also other small articles such as cigarettes and a lighter. Besides, it is difficult to take it out from a rear pocket of slacks, especially while sitting, since the rear pocket is comparatively small and obstructed by bulky loins.

Moreover, when being carried in the pocket of slacks, the portable telephone may suddenly fall out of the pocket due to one's physical motions such as walking, standing, and sitting.

Furthermore, when being carried in a pocket of a jacket, it may also fall out of the pocket on the occasion of taking off or putting on the jacket.

The Japanese Utility Model No. 3019172 discloses a special pocket for a portable telephone fixed at both sides of clothes. The Japanese Utility Model No. 3025210 discloses a pocket for a portable telephone fixed inside a conventional pocket.

However, these pockets can not prevent the portable telephone from suddenly falling out, and one needs to pay special attention when standing and sitting.

Therefore, an object of this invention is to improve a pocket for portable telephone in clothes such as a jacket and slacks.

SUMMARY OF THE INVENTION AND ADVANTAGES

The present invention is characterized by a pocket for portable telephone in clothes comprising a lower section provided horizontally in cloths with the width of 6 cm~9 cm, a bottom bag made of stretchy cloth with the comparatively shallow depth of 6 cm~11 cm, which is sewn to the lower section to be suspended behind the cloth, an upper section provided horizontally 2 cm~4 cm above the lower section with the same width thereof, and a head bag sewn to the upper section to stay upward behind the cloth with the height of 2 cm~4 cm. Because of this structure, about one third to a quarter of the portable telephone is always sticking out of the bottom bag, and some of the this part is inserted into the head bag. Accordingly, an upper part of the portable telephone is securely caught in the head bag, thereby causing none of the former troubles involved in the pockets of the prior art. Further, because the bottom bag made of stretchy cloth is effectively stretched, the portable telephone can be easily inserted and securely caught in the pocket.

The present invention is further characterized by a pocket for a portable telephone in clothes comprising a lower section provided horizontally in cloth with the width of 6 cm~9 cm, a bottom bag made of stretchy cloth with the comparatively shallow depth of 5 cm~10 cm, which is sewn

to the lower section to be suspended behind the cloth, at least one upper section provided 2 cm~4 cm above the right or left end of the lower section with the width of 2 cm~3 cm, and an antenna covering bag sewn to the upper section to stay upward behind the cloth with the height of 1 cm~3 cm. Because an antenna of the portable telephone is caught in the antenna covering bag, the portable telephone does not easily fall out regardless of one's physical motions such as standing and sitting. The antenna can be easily taken out of the antenna covering bag by only pushing an exposed upper part of the portable telephone downward a little, thereby effecting its easy use.

Moreover, in the present invention, an upper section with the width of 2 cm~3 cm is provided to have a fixed 15 inclination against the lower section. With this structure, the antenna of the portable telephone can be speedily inserted or taken out.

The above pocket for portable telephone is provided in cloth such as front body cloth or sleeve cloth in a jacket, and front body cloth or back body cloth in slacks. Accordingly, one can easily carry and use the portable telephone by wearing these clothes.

BRIEF DESCRIPTION OF THE DRAWINGS

25 FIGS. 1A and 1B show a first embodiment of this invention:

FIG. 1A is a partially cutaway front view; and

FIG. 1B is a sectional view taken along the line X—X of FIG. 1A.

FIG. 2 shows how to use a pocket disclosed in FIG. 1.

FIG. 3 through FIG. 7 show working examples of the pocket disclosed in FIG. 1.

20 FIGS. 8A and 8B show a second embodiment of this invention:

FIG. 8A is a partially cutaway front view; and

FIG. 8B is a sectional view taken along the line Y—Y of FIG. 8A.

FIG. 9 shows how to use a pocket disclosed in FIG. 8.

FIG. 10 and FIG. 11 show working examples of the pocket disclosed in FIG. 8.

DESCRIPTION OF PREFERRED EMBODIMENTS

45 Now a detailed explanation of this invention follows with attached drawings. FIG. 1A is a partially cutaway front view of a first embodiment of the invention, and FIG. 1B is a sectional view taken along the line X—X of FIG. 1A. As shown in these figures, a pocket for a portable telephone is formed in cloth 1, comprising a lower section 2 and an upper section 3.

50 The lower section 2 is formed horizontally in cloth 1. The width "w" thereof is usually within 6 cm~9 cm, though it can be suitably changed according to the size of a portable telephone 4.

55 A bottom bag 5 is sewn (m) to the lower section 2 so as to be suspended behind the cloth 1. The bottom bag 5 is made of different cloth of stretchy material in advance to form a cylindrical bag with the depth (h). Though the depth (h) can be also suitably changed according to the size of the portable telephone 4, it is usually within 6 cm~11 cm. Accordingly, the bottom bag 5 is shallow in depth in comparison with the phone. This is because not the whole of the portable telephone 4 is inserted in the bottom bag 5, but about one third to a quarter of an upper part thereof is always extending out of the bottom bag.

The upper section 3 is horizontally formed above the lower section 2 with the same width thereof in cloth 1.

A head bag 6 is sewn (m') to the upper section 3 so as to oppose the bottom bag 5 behind cloth 1 with the bottom of the head bag 6 extending upward. The head bag 6 is made of different cloth in advance to form a cylindrical bag with the height (h'). The height (h') is usually within 2 cm~4 cm. An exposed upper part 4a of the portable telephone 4 is caught and inserted in the head bag 6.

Here, an interval (s) between the lower section 2 and the upper section 3, both provided horizontally, can be suitably changed. However, according to experiments of this inventor, it is suitable to be within 2 cm~4 cm for an easy insertion of the portable telephone 4.

In this invention, at least the upper part 4a of the portable telephone 4 is caught in the head bag 6 when the portable telephone 4 is inserted into the bottom bag 5, thereby causing none of the former troubles of the prior art.

Since in this invention the bottom bag 5 is made of stretchy material, the portable telephone can be easily inserted due to a stretchy effect of the bottom bag 5. Moreover, the portable telephone 4 is suitable pushed upward due to repulsion, when being pressed downward in the bottom bag 5. Therefore, the exposed upper part can be easily caught in the head bag 6.

FIG. 2 shows how to use the pocket for portable telephone.

The cloth in which the above pocket for portable telephone is cloth for a jacket or slacks. More particularly, the pocket for portable telephone can also be formed in the jacket cloth at the chest or upper arm, and in slacks cloth below both side pockets or at the loins. The jacket is not limited to one type, but any kind of jackets with long or short sleeve which are worn in daily life, such as working clothes, a shirt, or a blouse.

FIG. 3 shows a pocket for portable telephone fixed at an upper arm on sleeve cloth of a jacket.

FIG. 4 shows a pocket for portable telephone fixed at the chest on front body cloth of a jacket.

FIG. 5 shows a pocket for portable telephone fixed at the chest on front body cloth of a shirt.

FIG. 6 shows a pocket for portable telephone fixed below a side pocket on front body cloth of slacks.

FIG. 7 shows a pocket for portable telephone fixed at loins on back body cloth of slacks.

Next, an explanation of the second embodiment of this invention follows.

FIGS. 8A and 8B relate to the second embodiment and show a modified example of the upper section 3 disclosed in the first embodiment. FIG. 8A is a partially cutaway front view, and FIG. 8B is a sectional view taken along the line Y—Y of FIG. 8A. FIG. 9 shows how to use the second embodiment. Here, the same marks are given to the same parts shown in the first embodiment.

In this embodiment as well, the lower section 2 is formed horizontally in cloth 1, and the bottom bag 5 is sewn to the lower section 2 so as to be suspended behind the cloth 1 as in the first embodiment.

On the other hand, at least one upper section 13 whose width (f) is comparatively small (within 2 cm~3 cm) is formed 2 cm to 4 cm above the right or left end of the lower section 2. Though in this figure the upper section 13 is formed to have a fixed inclination θ , it can be formed horizontal to the lower section 2. An antenna covering bag

16 is sewn (m") to each upper section 13 behind the cloth 1 as in the first embodiment. Here, the height (h") of the antenna covering bag 16 is within 1 cm~3 cm, so that an antenna 4b of the portable telephone can be easily caught in the antenna covering bag 16 when being inserted therein.

If the above upper section 13 is provided to both sides, the portable telephone can be easily and conveniently inserted in the tipper section 13 regardless of a location of the antenna 4b on the portable telephone 4. The inclination θ can be suitably changed. According to experiences of this inventor, however, it is most convenient to be within 15°~30°.

In this embodiment as well, the portable telephone 4 is inserted in or taken out of the pocket due to a stretchy effect of the bottom bag 5 as in the first embodiment. Since only the antenna 4b is caught in the antenna covering bag 16, the portable telephone 4 can be easily taken out by only pushing its upper part downward.

Working examples of this embodiment are same as in the first embodiment. That is, the pocket for portable telephone is formed in jacket cloth at the chest or upper arm, and in slacks cloth below both sides pockets or at loins. In this embodiment as well, the jacket is not limited to one type, but any kind of jackets with long or short sleeves, which are worn in daily life, such as working clothes, shirts, or blouses. Slacks can be of any kind, such as a working wear, casual wear, or sport wear. As particular examples, FIG. 10 shows the pocket below both side pockets of slacks, and FIG. 11 shows the pocket provided at the back of the slacks.

What is claimed is:

1. A pocket for a portable telephone in clothes made of cloth having opposite sides, said pocket comprising:
  - a first opening in said cloth, said first opening having a width;
  - a bottom bag made of stretchy material, said bottom bag having a depth that is shallow in comparison to the telephone, said bottom bag having an entrance portion defining a bag opening, said entrance portion being secured to said cloth around said first opening in said cloth to be suspended along one of the sides of the cloth;
  - a second opening in said cloth, said second opening being spaced from said first opening in said cloth and having a width substantially equal to the width of the first opening; and
  - a head bag having an entrance portion defining a bag opening, the entrance portion of the head bag being secured to said cloth around said second opening to stay along the same side of the cloth as the bottom bag.
2. A pocket for a portable telephone as set forth in claim 1:
  - wherein said cloth is a front body cloth of a jacket.
  3. A pocket for portable telephone as set forth in claim 1: wherein said cloth is sleeve cloth of a jacket.
  4. A pocket for portable telephone as set forth in claim 1: wherein said cloth is front body cloth of slacks.
  5. A pocket for portable telephone as set forth in claim 1: wherein said cloth is back body cloth of slacks.
  6. A pocket for a portable telephone as set forth in claim 1, wherein each of said first and second openings comprises a slit.
  7. A pocket for a portable telephone as set forth in claim 6, wherein said slits are parallel to one another.
  8. A pocket for a portable telephone as set forth in claim 6, wherein each of said slits has a length of about 6 cm to about 9 cm.

9. A pocket for a portable telephone as set forth in claim 1, wherein a portion of said cloth extends between said first and second openings.

10. A pocket for a portable telephone as set forth in claim 1, wherein one of said opposite sides of said cloth is an interior side facing a wearer of the clothes, and said bottom bag and said head bag are positioned along said interior side of said cloth.

11. A pocket for a portable telephone as set forth in claim 1, wherein the entrance portion of the bottom bag is sewn around said first opening, and the entrance portion of the head bag is sewn around said second opening. 10

12. A pocket for a portable telephone as set forth in claim 1, wherein the bottom bag has a depth of about 6 cm to about 11 cm.

13. A pocket for a portable telephone as set forth in claim 1, wherein said first opening is spaced about 2 cm to about 4 cm from said second opening.

14. A pocket for a portable telephone as set forth in claim 1, wherein the head bag has a depth of about 2 cm to about 4 cm. 10
